UNITED STATES PATENT OFFICE.

CARL E. M. MILLER, OF NEW YORK, N. Y.

LIFTING-TRUCK.

1,139,891.

Specification of Letters Patent. Patented May 18, 1915.

Application filed July 3, 1914. Serial No. 848,729.

To all whom it may concern:

Be it known that I, CARL E. M. MILLER, a citizen of the United States, and a resident of the city, county, and State of New York, 5 have invented a new and useful Improvement in Lifting-Trucks, of which the following is a full, clear, and exact description.

My invention relates to improvements in lifting trucks of a class in which one portion 10 of the truck is movable vertically with relation to the other portion, so that the truck can be slid under its load, and the upper part raised so as to lift the load from the floor and render it readily transportable. 15 In trucks of this class the raising of the upper frame is usually effected by a lever or by a movement of the handle, but it has been found in the development of such trucks that it is very desirable to provide an easy 20 means of manipulating the truck to raise its load, and that it is then very necessary to leave the front wheels and the handle free so as to turn readily. In carrying out this idea it has been the practice to provide a 25 detachable connection between the movable top frame of the vehicle, and the handle, and to provide means for detaching this connection after the said frame has been raised and fastened in place by some means. This 30 means of detaching, however, has generally been operated independently of the handle, either by hand or by foot power, and it is a great inconvenience.

The object of my invention is to produce 35 a simple connection between the movable top frame of a truck of this class and the handle, by which the handle can be used as a lever to raise the frame, and also to provide an automatically releasing connection so that 40 by the mere manipulation of the handle, the connection between the handle and the movable top frame can be released or fastened as desired. With my improved apparatus the truck can be slipped under its load, the handle brought forward to raise the load, and then when the handle is in normal position 45 to draw the truck about, it will automatically release itself from its connection with the movable frame so as to leave the forward wheels free to turn, and the connection 50 between the handle and frame can be easily entirely disconnected so as to provide the necessary freedom of movement.

Reference is to be had to the accompanying 55 drawings forming a part of this specification, in which similar reference characters

indicate corresponding parts in all the views.

Figure 1 is a broken side elevation of a truck showing my improvements, with the top frame in its lowest position. Fig. 2 is a similar view but with the top frame raised. Fig. 3 is a broken front elevation of the truck. Fig. 4 is a broken side elevation of the front portion of the truck and showing a different position of the engaging hook from that disclosed in Figs. 1 and 2. Fig. 5 is a broken side elevation similar to Fig. 4, but showing the position the handle and connected parts assume when the top frame is brought to its most elevated position. Fig. 6 is a broken plan view of the front part of the truck, and Figs. 7 and 8 are details.

My invention relates principally to the means for sliding and disconnecting the top frame. The truck is provided with a suitable frame 10 which is mounted in any convenient manner on rear wheels 11, and at its forward end the lower frame 10 has an upward and forward extension 12, the front part of which merges into the top plate 13 of the fifth wheel, to facilitate turning the front truck or wheels. Beneath the plate 13 is the bottom plate 14 of the fifth wheel, which has integral depending side arms 15 from which extends the front axle 16, and this has suitable wheels 17 thereon. All this I have not shown with any great detail, because I do not here claim it.

The truck has a suitable top frame 18 which can be raised or lowered with reference to the frame 10 and this has on opposite sides depending wings 19 and 20 in which are inclined ways 21 and 23 respectively, the ways 21 riding on rollers on the axle 22, while the ways 23 receive the rollers 24 on the cross-bar 25 which is supported in the extension 12. It will be seen that when the frame 18 is drawn forward it will ride up on the rollers 24 and rear axle 22, so that the frame will be at the same time elevated. It will also be observed that as the parts 22 and 25 project into the ways 19 and 23, the frames 18 and 10 will be held in proper relation, and the frame 18 cannot be lifted off or displaced.

Near its front end the frame 18 has bosses 27 through the front upper portion of which extends a cross-bar 28 which can be engaged by a hook 29, this being arranged so as to normally ride on the cross-bar 28. The hook 29 is split near its pivoted end as shown at

30 (see Fig. 6), and it is pivoted as shown at 31 to the link 32 which is in turn pivoted as shown at 33 in a bifurcated socket portion 34 of the handle 35. The part 34 is in turn pivoted between the ears 36 which are integral with the plate 14 of the fifth wheel. The ears 36 have rearwardly extending arms or parts 37 which serve to support the pin 31 which is the pivot of the hook 29 when the parts are in a certain position, and this prevents the hook from dropping down too far.

In the bifurcated part of the hook 29 is pivoted the shank 39 of the pawl 40 (see Fig. 7), which rides on the top of the hook and which when the hook is level or nearly so, drops by gravity over the tooth 41 on the hub of the hook 29, and thus prevents the hook 42 from dropping in engagement with said tooth. The hook 42 is pivoted in the part 34 just above the link 32, and it is provided on its under side with projections 43 adapted to be brought into and out of registry with corresponding projections 44 on the link 32, so that when the projections 43 and 44 are in registry, the hook will be held out of engagement with the tooth 41; but when the said projections are out of registry, the hook is free to drop into engagement with the tooth.

Assuming the frame 18 to be in its lowest position as shown in Fig. 1, with the handle 35 raised. The device is pushed beneath its load, and then the handle 35 is brought forward to the position shown in Fig. 5. This causes the hook 29 to engage the bar 28 and pull the frame 18 forward, thus raising it as above described, and it is held in its raised position by a suitable mechanism 40 which is not here shown, as it forms no part of this invention. The handle can then be raised to the normal position for hauling the truck around, and the hook 29 will ride on the cross-bar 28 without interfering with the free movement of the truck; but if it is desired to give still greater freedom of a lateral movement, and to remove the hook 29 entirely away from the cross-bar 28, the handle can be raised until the hook 42 drops into engagement with the tooth 41, and then the handle is brought forward to the position shown in Fig. 4, thus raising the hook 29 and permitting the handle to turn sideways or vertically with the utmost freedom, and in its side movement it will of course turn the plate 14 of the fifth wheel and serve to guide the truck. When it is desired to again place the hook 29 in engagement with the cross-bar 28, the handle is pushed back to the position shown in Fig. 2, thus carrying the hook 42 back of the pawl 40, and then the handle can be brought forward, when the hook 42 will ride over the pawl will be held out of engagement 65 with the tooth 41 by reason of the register-

ing projections 43 and 44 on the hook 42 and link 32. When, however, the handle is pushed back for the purpose of having the hook 42 engage the tooth 41 as hereinabove described, the projections 43 and 44 are out 70 of registry, and the pawl 40 hangs vertically so that the hook 42 can readily drop between it and the tooth 41.

The handle 35 cannot be tipped back farther than shown in Fig. 1, by reason of the 75 stop 34^a (see Fig. 2) on the lower portion of the socket member 34, which stop engages the plate 13 and checks the backward movement of the handle.

If it is desired to lock the handle in its 80 raised position, it can be done by means of the pawl 45 (see Figs. 2 and 3), which is pivoted in one of the ears 36, and which can be tipped forward in front of the handle as in Fig. 3 to hold the handle in its raised 85 position.

From the foregoing description it will be seen that I have devised a very simple means of connecting and disconnecting the handle with the movable top frame, and that no 90 manipulation of any extraneous parts is necessary to effect the engagement or disengagement of the handle.

I claim:—

1. In a truck of the kind described, the 95 combination with the upper and lower frames, the upper frame being movable longitudinally and vertically with relation to the lower frame, of a vertically swinging handle connected to the front end of the 100 truck, a cross-bar on the top frame, a hook riding on and engaging the cross-bar, said hook having a link connection with the handle, a second hook pivoted to the handle and riding above the first hook, and means 105 controlled from the handle for placing the second hook into or out of engagement with the first hook whereby the latter may be raised or lowered.

2. The combination with the truck and its 110 movable top frame, of a handle pivoted on the front part of the truck, a link carried by the handle, a hook pivoted to the link and adapted to engage with the movable top frame, said hook having a tooth thereon, a 115 second hook pivoted in the handle above the link and adapted to drop into engagement with the aforesaid tooth, and a pawl pivoted in the hook and adapted to drop between the tooth and the aforesaid second 120 hook.

3. The combination with the truck having a movable top frame, of a handle pivoted on the front portion of the truck, a link pivotally connected with the handle, a hook 125 pivoted to the link and provided with a tooth near its hub, means on the top frame to engage the hook, a second hook pivotally connected with the handle and adapted to engage the aforesaid tooth, means on the 130

link and second hook to control the movement of the second hook with relation to the aforesaid tooth, and a pawl on the first hook adapted to drop between the tooth and the second hook.

4. The combination with the truck, its movable top frame, and the pivoted handle near the front end of the truck, of the link pivoted to the handle and provided with 10 projections on its top side, the hook pivoted to the link and provided with a tooth,

means on the top frame to engage the hook, a second hook pivoted to the handle and provided with projections riding on those of the link, and a pawl on the first hook 15 adapted to drop between the tooth of said hook and the second hook.

CARL E. M. MILLER.
